UNITED STATES PATENT OFFICE.

JAMES NEWELL GRAVES, OF SAN SABA, TEXAS.

BOLL-WEEVIL DESTROYER.

1,239,684.

Specification of Letters Patent. Patented Sept. 11, 1917.

Application filed March 7, 1917. Serial No. 153,121.

To all whom it may concern:

Be it known that I, JAMES NEWELL GRAVES, a citizen of the United States, residing at San Saba, in the county of San Saba, State of Texas, have invented a new and useful Boll-Weevil Destroyer; and I do hereby declare the following to be a full, clear, and exact description of the invention, such as will enable others skilled in the art 10 to which it appertains to make and use the same.

This invention relates to an improved boll weevil or other insect destroyer, and an object of the invention is to provide a 15 suitable receptacle for containing a suitable poisonous solution, into which the insects are drawn by means of a suitable fan.

A further object of the invention is to provide a rocking shaft on which a pair of 20 agitators are mounted, in combination with means receiving power from the supporting wheels of the frame of the machine for oscillating said agitators.

In practical fields, the details of construction 25 may necessitate alterations falling within the scope of what is claimed.

The invention comprises further features and combination of parts, as hereinafter set forth, shown in the drawings and claimed.

30 In the drawings:—

Figure 1 is a plan view of a destroyer constructed in accordance with the invention.

Fig. 2 is a sectional view on line 2—2 of 35 Fig. 1.

Fig. 3 is a transverse sectional view on line 3—3 of Fig. 1.

Fig. 4 is a sectional view on line 4—4 of 40 Fig. 1.

45 Referring more especially to the drawings, 1 designates a tongue to which a frame 2, is secured. This frame 2 comprises the bars 3, which are angular in plan view and have their parts 4 secured by bolts 5 to the tongue. The rear ends of the bars have sleeves 6, which are secured on the upright portions 7 of the U-shaped axle 8, by means of the set bolts 9. The upright portions 7 of said axle at their lower parts, terminate 50 in the spindles 9^a, on which the supporting or drive wheels 10 are mounted. One of the drive wheels is provided with gear teeth 11. An elongated casing 12 is suspended from the arched portion of the axle 8 by means 55 of the straps 13. The front of the casing has an opening 14, which is covered by the

closure 15 hinged at 16. A curved partition 17 is mounted on the interior of the casing 12 so as to divide off a fan chamber 18. A shaft 19 is mounted in bearings of the casing, and on the shaft 19 a fan 20 is mounted to rotate with the shaft. The partition 17 is of a curvature to correspond with curvature of the fan, and is provided with a curved lip 21. A piece of wire fabric 22 extends from the lip 21 and is connected to the front wall of the casing 12. The rear wall of the casing 12 at its upper portion has an opening 23, which is covered by a piece of wire fabric 24. Depending downwardly from each end of the casing 12 are auxiliary casings 25 having pneumatic passages 26. Connected at 27 to the two sides and the rear wall of the lower end of each casing 25 is a suitable flexible skirt 28, preferably constructed of leather or the like. It is to be noted that as the machine travels over the field, the casings 25 pass over the rows of plants, said skirts, therefore, in this case, ride over the tops of the plants, and 80 as the insects or boll weevils have been shaken from the plants, the insects and the like are drawn upwardly through the passages 26, and over the lip 29 and into the poisonous solution 30, which is contained 85 in the lower part of the casing 12. The fan 20 creates a suction in the passages 26, drawing the air through the screen 22 and forcing it out through the screened opening 23, the insects dropping into the poisonous 90 solution. An arm 31 projects rearwardly from the lower part of one of the uprights of the axle 8, and in a bearing of the free end of this arm, a stub shaft 32 is mounted, having the collars 33 to prevent axial movement of the stub shaft. One end of the stub shaft has a pinion 34 while its other end is provided with a sprocket 35, about which a chain 36 engages. On both ends of the shaft 19 are sprockets 37 and 38, the sprocket 37 95 being engaged by the sprocket chain 36, while the sprocket 38 is engaged by a sprocket chain 39. One end of a shaft 40 is secured in a bearing 41 (which depends downwardly from the tongue 1) by means 100 of the set bolt 42. The other end of the shaft 40 is mounted in a bearing 43 of the cross piece 44, which extends from one side of the frame to the other. Mounted to rock upon the shaft 40 are the sleeves 45, 46 and 110 47. The sleeve 46 is prevented from axial movement by the collars 48, which are

pinned on the shaft 40. Extending downwardly from the sleeve 46 are the arms 49, which are disposed V-shaped relative to each other. Extending down from the sleeve 45 is an arm 51, and depending from the sleeve 47 is an arm 52. The arm 51 extends at an angle or an inclination corresponding to that of one of the arms 49, while the arm 52 extends at an inclination corresponding to that of the other arm 49. A suitable plate 53 is connected to one of the arms 49 and the arm 51, while a second plate 54 is connected to the other arm 49 and the arm 52, thereby providing a pair of agitator blades, 15 which, through the medium of the sleeves 45, 46 and 47, are suspended from the shaft 40, so as to be rocked. Extending upwardly from the sleeve 46 is an arm 55, and mounted in bearings 56 of the bars 2 is a shaft 20 57 having a sprocket 58 at one end to be engaged by the sprocket chain 39. Carried on and rotatable with the shaft 57 is a drum 59 provided with a cam groove 60, which receives the arm 55. This cam groove 60 25 is so constructed, that when the shaft 57 is rotated, the sleeve 45 will rock, and with it, the sleeves 46 and 47, thereby oscillating the agitator blades, which will come in contact with the top of the plants or the like, 30 shaking them sufficiently to cause the insects to fall therefrom and be drawn by the suction through the passages 26 and de-

posited into the poisonous solution. By means of the pinion 34 engaging the teeth 11, and through the medium of the chains 35 36, motion is imparted to the shaft 19, which transfers motion to the shaft 57, which oscillates the agitator.

The invention having been set forth, what is claimed as new and useful, is:—

In an insect destroyer, a frame having an axle provided with supporting wheels, a casing suspended on the axle provided with a receptacle for a poisonous solution, said casing having at its ends downwardly depending pneumatic passages provided with flexible skirts to drag over the plants and the like, a fan journaled in bearings of the casing to create suctions in said passages, to draw the insects into the casing, means for deflecting the insects into the solution, means of connection between the fan and one of the supporting drive wheels to impart motion to the fan, and an agitator, for shaking the insects from the plants, whereby they may be sucked into said passages.

In testimony whereof I have signed my name to this specification in the presence of two subscribing witnesses.

JAMES NEWELL GRAVES.
